SWITCH CONTROL CIRCUIT

Herbert Jackson, St. Helens, England, assignor to
 Radio Corporation of America, a corporation of
 Delaware

Application May 25, 1939, Serial No. 275,691
 In Great Britain May 26, 1938

7 Claims. (Cl. 175—320)

The present invention relates to electro-magnetic relays, and is concerned with relays of the direct current type which are adapted to function reliably on alternating current by using them in conjunction with metal rectifiers.

The method usually employed is to connect the metal rectifier in parallel with the energising coil of the relay and, in consequence, the switch contacts (or, it may be, the contacts of another relay) which open and close the circuit of the relay must necessarily be in direct electrical connection with the alternating current supply. There are many cases in which such direct connection is disadvantageous. For example, if the relay were employed for the remote switching of a radio receiver it is obvious that the remote control wiring would have to be as well insulated and protected as the ordinary house lighting mains. A transformer could, of course, be used, but this would add materially to the cost of the remote switching unit. It is an object of the present invention to provide an arrangement whereby the control circuit of the relay is insulated from the alternating current supply, and which, moreover, works at a voltage low enough to be harmless should faults develop in the control circuit wiring.

According to the invention an electro-magnetic relay possesses two windings insulated from each other, one continuously connected across the alternating current supply, and the other connected to a metal rectifier and control contacts on a manual switch, or another relay.

According to another feature of the invention the winding which is connected to the alternating current supply is positioned near the heel-end of the relay core, while the other winding which is connected to the metal rectifier is positioned near the armature-end of the core.

According to a further feature of the invention the metal rectifier is in parallel with the control contacts and both are connected across the armature-end winding of the relay.

The two preceding paragraphs refer in particular to a preferred embodiment of the invention, and it must be understood that relays could be designed according to the main principle of the invention (as set out in the last paragraph but two above) but with the two windings one over the other and/or the rectifier and control contacts connected in series across the control winding. Moreover, the invention is not limited to any particular design of the magnetic circuit of the relay and of its contact spring assembly, but in order that the invention may be better under-

stood the following description is given, for example, only, of methods of carrying it into effect employing a relay of the type used extensively in automatic telephone systems and showing how the remote switching of a radio receiver may be effected by the use of the relay.

In the drawing:

Fig. 1 shows one embodiment of the invention,
 Fig. 2 shows a modification, and,

Figure 3 illustrates a type of relay which may be used with the arrangements shown in Figures 1 and 2.

The relay is well known and comprises an L-shaped yoke member L (Figure 3), two windings 1 and 2 being mounted on a core C parallel to the longer limb of the yoke member, an armature A being pivoted to the yoke member opposite the free end of the core and a spring contact assembly S mounted on the yoke member and adapted to be operated by an extension E of the armature A. In this particular case the disposition of the windings 1 and 2 is similar to that adopted in the case of the impulse-responding relay on a selector switch, that is to say the winding space is divided into two compartments separated by an insulating spool cheek W, although the two compartments are not necessarily equal in size as is usually the case in impulsing relays. The heel-end winding 1 is connected across the current supply 4 (Figure 1) and its impedance is high enough to limit the current drain to very small proportions. When intended to provide remote switching facilities for radio receivers already installed, the relay may conveniently be mounted in a suitable box together with a metal rectifier 5 which is permanently connected across the armature-end winding 2 of the relay. The ends of the winding are also brought out to two terminals 6 and 7 on the box for connection to the remote control wires 8 to the positions of the remote loudspeakers LS. The latter are preferably each fitted with a volume control which may operate an on-off switch 9 at the minimum volume setting, in the well-known manner.

Referring to Figure 3, it will be seen that when armature A is contracted switch 3' is opened and switch 3 is closed. It is thus seen that when this arrangement is used with the arrangement shown in Figure 1, only the switch 3 is used through connection of conductors 10 and 11 as shown in Figure 1 and switch 3' is not used; that is, conductor 12 shown in Figure 3 is not connected to anything.

The wiring of the remote control wires is such that the on-off switches at the various remote

points are all connected in series across the armature-end winding 2 of the relay. This series connection is necessary because the "off" position at each switch corresponds to a closure of the switch contacts and when the switch is put in the "on" position its contacts are opened. Therefore, when all the remote switches are in the "off" position the armature-end winding 2 of the relay is thereby short-circuited (providing the resistance of the remote control wires is kept low which is usually the case). Not only, therefore, is the action of the rectifier nullified but, in addition, the short-circuited winding acts as an armature-end slug, and thus effectively prevents the relay from operating even though the heel-end winding 1 is connected to the alternating current supply.

When any one, or more, of the remote switches is thrown to the "on" position the short-circuit is removed, and the rectifier acting in conjunction with the armature-end winding 2, which is functioning like the secondary winding of a transformer, allows the relay to operate and close its make-contacts 3 which connect the radio receiver to the current supply. The heel-end winding 1 may conveniently be connected to a plug for connection to the current supply, while inside the box the heel-end winding terminals are also connected by the relay make-contacts to a socket on the side of the box adapted to receive the mains plug of the radio receiver.

Fig. 2 shows a modification bearing self-explanatory legends. The remote switches 9 are here in parallel. This is accomplished by fitting the relay with "break" contacts instead of "make" contacts shown in Fig. 1. When all of the remote switches are "off" as shown in Figure 2 the relay is operated, and the receiver is "off" that is, switch 3' is opened. Faulty switches, that is poor contact in the "on" position, cannot cause the set to be switched on prematurely. The standing power drain from the mains is about 2 watts. The metal rectifier is extremely small; they can be merely two discs of $\frac{3}{4}$ inch diameter and $\frac{1}{16}$ inch thick. It can be seen that for the arrangement shown in Figure 2 only the switch 3' of the relay shown in Figure 3 is used and the connection is made through conductors 11 and 12 corresponding to conductors 11 and 12 of Figure 2.

Finally it will be realized that the relay and rectifier may be employed to effect the remote switching of any other form of electrical appliance, and their functioning in every case will be substantially similar to that above described.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. In an arrangement for connecting an electrical appliance to a power supply network, a transformer comprising a primary winding connected to said network and a secondary winding, a rectifier connected across said secondary winding, switching means operable to short-circuit said rectifier and thereby render it inoperative, an armature positioned adjacent said secondary winding and adapted to be attracted thereby only when said rectifier is in operation, said armature acting as a switching means to connect and disconnect the electrical appliance to said network.

15 2. The arrangement described in claim 1 wherein said switching means operable to short-circuit the rectifier are located at a point remote from said appliance and wherein the appliance is connected to the network so as to be energized when the short-circuit is removed from the rectifier by operation of the remote switching means and disconnected from the network when the rectifier is short-circuited by operation of the remote switching means.

20 3. The arrangement described in claim 1 wherein the appliance through operation of the armature is connected to the network so as to be energized when said rectifier is short-circuited by the switching means and thereby rendered inoperative and disconnected from the network when the short-circuit is removed by the operation of said switching means.

25 4. In an arrangement for connecting an electrical appliance to an alternating current source, a circuit including a control switch for connecting and disconnecting said appliance to the source, a relay comprising a pair of reactively coupled windings, one of said windings being connected across said source, means for deriving a uni-directional current from the alternating current transferred from the source to the other of said windings through said reactive coupling, said means being arranged so as to cause the uni-directional current to flow through said other winding, means for controlling the operation of said control switch in accordance with the flow of uni-directional current in said other winding, and means for selectively rendering said deriving means ineffective.

30 5. The arrangement described in claim 1 wherein said switching means comprises a plurality of selectively operable switches connected in series across the rectifier.

35 6. The arrangement described in claim 1 wherein the switching means comprises a plurality of selectively operable switching devices connected in parallel across the rectifier.

40 7. The arrangement described in claim 1 wherein the switching means is operable to short-circuit both the rectifier and the secondary winding.

HERBERT JACKSON.
